Moore Hardaway

UNITED STATES PATENT OFFICE.

MOORE HARDAWAY, OF ST. LOUIS, MISSOURI.

IMPROVEMENT IN HORSESHOE-MACHINES.

Specification forming part of Letters Patent No. 40,689, dated November 24, 1863.

To all whom it may concern:

Be it known that I, MOORE HARDAWAY, of the city and county of St. Louis, and State of Missouri, have invented a new and useful Improvement in Machines for Bending or Forming Horseshoes; and I do hereby declare that the following is a full and clear description thereof, reference being had to the accompanying drawings, and to the letters of reference marked thereon and made to form a part of this specification.

This invention relates, first, to the employment of horseshoe-forms, in combination with a rotating disk; second, in combination with said forms and disk, the use of certain clamps; and, third, to a device for releasing the formed shoes, all being constructed and arranged to operate substantially as hereinafter set forth, specified, and represented.

In reference to the accompanying drawings, Figure 1 is a perspective view of my improvement. Fig. 2 is a plan or top view. Fig. 3 is a sectional front elevation, and Fig. 4 is a sectional view of the disk and device for releasing the formed shoes.

A represents the platform or bed of the machine, which may be supported by suitable posts, A', and the said posts may be strengthened by means of braces B B'.

C represents the rotating disk, which will be formed of suitable material, metal being preferred, and may be sustained so as to rotate in proper position by means of a suitable arbor having bearings in supports d d' of the bed A. The said disk may be provided with a driving cog-wheel, D, by means of which the same may be operated.

f represents the forms around which the blanks will be bent. Said forms will be of suitable metal, and will be secured at equal distances upon the front face of the disk C, as clearly represented in Fig. 3, in such manner that they may be detachable, so that, if desired, different forms varying in size, in such manner as to be adapted to the different sizes of shoes required, may be employed. In the machine here represented, four of the said forms are used, so that the machine is capable of forming four shoes during each revolution of disk C; but a greater or less number of said forms may be employed, the other working parts of the machine being constructed and arranged with reference to the number of

forms to be used. The peculiar configuration of the said forms f will, as nearly as possible, be that of the most perfect known form for horseshoes.

g g' represent the clamps, arranged in duplicate upon the bed C, their rear ends being hinged or pivoted, as clearly shown in Figs. 1 and 2, in such manner as to allow lateral motion to their forward ends, which are provided with the formers e e'. These formers extend forward so as nearly to touch the face of the disk C, and are formed with projecting shoulders, so constructed and arranged that suitable spaces may be afforded between the said shoulders and the face of the disk to receive the blanks which are to be formed. The said shoulders are adapted to hold the blanks in proper position while they are being forced between the formers by the forms f.

h h' represent cams, which are firmly secured to the clamps g g'.

i i' represent bars firmly secured to standards j j', (seen distinctly in Fig. 3,) and provided with friction-rollers k k'.

l l' represent bars arranged upon the braces B in such manner as to be prevented from lateral motion and allowed horizontal motion. The said bars l l' are provided with friction-rollers m m', and are rigidly secured to the standards j j'.

n represents cams arranged upon and secured to the rear face of disk C in such manner as to be adapted to come in contact with the friction-rollers m m' at proper periods in the operation of the machine, thereby actuating the said bars l l' and standards j j', so as to cause the bars i i' to move forward, thereby forcing the rollers k k' to bear against the cams h h' of the clamps g g', thereby compressing or contracting said clamps in such manner that the formers e e' will necessarily force the blanks into the configuration of the forms f. The said bars l l', standards j j', bars i i', and rollers k k' will be retracted by means of suitable springs. The said bars l l' may be arranged upon the top or face of the bed A, if desired, thereby dispensing with the standards j j'.

p p' represent brackets, which are adapted to confine the clamps g g' in their proper position for operation.

s represents the releasers, which are adapted to remove the bent shoes from the forms. They

are provided with pins s' , which are made to pass through the disk to its front face, and also with springs s'' , (seen in Fig. 4,) which are adapted to prevent the said pins from projecting out beyond the face of the disk, except at certain periods in the revolution of said disk, when the releasers s are made to pass under projections $t t'$, above and below the bed A , by means of which the said springs will be compressed, and the pins s' forced out against the formed shoes in such manner as to release them from the forms f and the disk C .

Having thus described the construction of my improvement, I will explain briefly its operation.

The working parts of the machine being nearly in the position shown in Figs. 1 and 2, and the disk being made to rotate in the direction of the arrows, blanks, heated in a suitable manner, may be fed to the machine upon each side at the same time. Upon the right-hand side, (looking toward the front face of the disk C ,) the blank will be fed above the formers, and upon the left-hand side below the formers. As the disk C continues to rotate, the said blanks will be carried upon the forms f , between the formers $e e'$ of the clamps $g g'$, before described, and there bent into the proper form by the compressing action of the said clamps, through the medium of cams $h h'$, rollers $k k'$, bars $i i'$, standards $j j'$, bars $l l'$, and

cams n , as previously set forth. The shoe thus formed upon the right hand of the machine will be removed from its form by means of a releaser, s , passing under the projection t , and the shoe formed upon the left of the machine will in like manner be released by means of the projection t' . When the said clamps have been released by the retraction of bars $l l'$, they will be expanded, so as to be ready to operate again, by means of springs $x x'$.

Should it be found necessary, suitable rollers may be arranged in such manner that the forms f , together with the formed shoes, may pass under them, in order to remove any kinks or wrinkles that may arise at the toes of the shoes during the process of bending.

Having thus described my improvement, what I claim as new and of my own invention, and desire to secure by Letters Patent, is—

The arrangement and combination of the rotating disk C , forms f , and clamps $g g'$, all being constructed and adjusted to operate substantially as and for the purpose set forth.

In testimony of which invention I have hereunto set my hand and seal, this 25th day of September, 1863, in presence of witnesses.

MOORE HARDAWAY. [L. S.]
